DOORKNOB

Edgar Courtney Gadpaille, New Orleans, La.

Application August 25, 1947, Serial No. 770,347

1 Claim. (Cl. 292—353)

1

The present invention relates to improvements in door knobs and its general object is to provide a screwless burglar-proof door knob which cannot be removed from the exterior side of the door.

Another object is to provide a novel door knob arrangement which is quicker and easier to install than the usual screw type door knobs.

A further object is to provide a novel door knob fastening means in combination with release means on the interior side only of the door for said fastening means.

With these and other objects in view which will become apparent as the invention is fully understood, the same resides in the novelty of construction, combination and arrangement of elements hereinafter specifically described and distinctly claimed in the appended claim.

The description should be read in connection with the accompanying drawings wherein:

Fig. 1 is a cross section view of the door knobs and fastening means therefor mounted in a door latch;

Fig. 2 is an isometric view of the door knob spindle or shaft and of a door and latch bushing in cross section;

Fig. 3 is a front elevational view of the split end of the knob shaft;

Fig. 4 is a longitudinal cross section view of the knob shaft ratchet housing; and

Fig. 5 is an isometric view of the said ratchet housing as it appears removed from within a door knob.

Fig. 6 illustrates another form of the door knob, wherein the ratchet housing is formed from the door knob material as one integral part thereof.

Referring in detail to the several views, there is shown in Fig. 1 a door knob assembly comprising a shaft 10 formed with a substantially square center portion 11 bounded by a pair of apertured spacer members or disks 14 and 15. These members 14 and 15 are formed to slide onto the shaft 10 over the ends of the portion 11 until they engage against the interior and exterior respectively of a door B. The ends of the shaft 10 continuing from the substantially square center part 11 are bifurcated so as to form two yieldable arms 16 and 17 at each end.

The top flat surface of each of the arms is formed with ratchet lugs or teeth 18 facing in the direction of each side of the door B. These ratchet lugs 18 are adapted to operatively engage with generally similar but oppositely facing ratchet lugs 20 formed in the substantially square interior bore of a housing 21.

The housing 21 is preferably cylindrical around

its exterior and includes a plurality of radial lugs 23 formed from and near an end thereof. These lugs 23 serve to anchor the ratchet housing within the body of the door knobs 30 and 31, as shown in Figure 1. The door knobs are preferably made of plastic or glass, but any suitable material may, of course, be used. Thus, each door knob is made with one of the ratchet housings 21 embedded therein. However, the housings 21 are so arranged in the knobs that the shanks 33 are flush with an open end of the housing bore, to thereby provide a ratchet socket in each knob to receive the ratchet toothed yieldable arms 16 and 17 of the shaft 10.

Accordingly, when the ends are inserted into the knob housings 21, the oppositely faced ratchet teeth 18 and 20 of the shaft and housing engage to lock the knobs onto the shaft ends against the spacer disks 14 and 15 on each side of the door B. The knobs 30 and 31 are distinguishable from each other as one is made solid over an end of the ratchet housing 21 and is applied to the shaft 10 on the exterior side of the door B. The other knob 31 at its rounded head portion is formed with a threaded opening surrounding an open end of the ratchet housing therein. Thus, when the shaft is inserted in the ratchet housing, the arms 16 and 17 of this end project from the bore beyond the end of the housing concentrically within the threaded opening in the knob. The threaded opening is counter-sunk from an annular shoulder 35, which serves as a stop and seat for a threaded cover plate 37.

The cover plate 37 is exteriorly recessed and formed with a groove 38 for a screw driver or the like. Thus, the plate is easily applied and removed to expose the free ends of the arms 16 and 17 in ratchet locking engagement inside the knob ratchet housing 21. Once the knobs are installed over the ends of the shaft 10, the ratchet teeth prevent the removal of the knobs from the shaft and knob 30 on the outer side of the door B becomes permanently attached. However, the knob 31 may be removed by detaching the cover plate 37 and squeezing the exposed ends of arms 16 and 17 together to release the locking engagement of the ratchet teeth 18 and 20. Thus, the knob assembly may be removed to repair the latch in the door when necessary, but only from the inside or the interior of the house or room which the door serves.

In Figure 6 the door knob and ratchet housing are formed as one element. The ratchet teeth 55 20, for example, are formed from the door knob

material by cutting, forging, or molding the same as the door knob is made.

Without further description, the operation should be apparent.

Although only two embodiments of the invention have been illustrated and described in detail, it is to be expressly understood that the invention is not limited thereto. For example, various changes may be made in the design and arrangement without departing from the spirit and scope of the invention, as will now likely occur to others skilled in the art. For a definition of the limits of the invention, reference should be had to the appended claim.

What I claim is:

A screwless knob assembly comprising in combination a latch spindle having a squared center portion and extending at each side thereof into bifurcated yieldable arms, a plurality of lugs formed on the top flat surfaces of the yieldable arms, and a knob, the knob having integrally united therewith a housing, said housing having lugs extended therefrom which are adapted to be embedded within the knob material, said housing having a longitudinal square opening extending therethrough, a plurality of lugs formed on

the upper and lower surfaces of the opening, the lugs on the knob housing engaging the lugs of the yieldable arms to lock the knob to the end of the spindle, the knob facing the inner side of the door having a removable screw cap fitting in the face thereof, whereby removal of said cap gives access to the yieldable arms to flex the same inwardly and disengage the knob and spindle lugs to remove the inside knob.

EDGAR COURTNEY GADPAILLE.
